The ornamental design for a guillotine, as shown and described.

DESCRIPTION

FIG. 1 is a top front and side perspective view of a guillotine, showing my new design;

FIG. 2 is a view similar to FIG. 1, the clamping arm being in an opened position;

FIG. 3 is a front elevational view of FIG. 3;

FIG. 4 is a rear elevational view thereof;

FIG. 5 is an end elevational view thereof; taken from the left of FIG. 3;

FIG. 6 is an end elevational view thereof; from the side opposite to that shown in FIG. 5;

FIG. 7 is a top plan view thereof; and,

FIG. 8 is a bottom plan view thereof.
